R. Kinsley,
Tobacco Press.

No 13,790.

Patented Nov. 13, 1855.

Inventor,
R. Kinsley

UNITED STATES PATENT OFFICE.

R. KINSLEY, OF LYNCHBURG, VIRGINIA.

IMPROVEMENT IN TOBACCO-PRESSES.

Specification forming part of Letters Patent No. 13,790, dated November 13, 1855.

To all whom it may concern:

Be it known that I, RHODOLPHUS KINSLEY, of Lynchburg, Campbell county, in the State of Virginia, have invented certain new and useful Improvements in Machinery for Compressing Tobacco, which are also applicable to the compression of other materials; and I do hereby declare the following to be a full, clear, and exact description thereof, reference being had to the accompanying drawings, in which—

Figure 1 is a cross-section; Fig. 2, one of the angle-plates detached. Fig. 3 is a perspective of the box with the parts all in place.

The object of my invention is to compress lumps of tobacco with rapidity and let it stand under pressure for sometime till it is set, using therefor but a single press, to effect which I employ a series of boxes, which I call "compressors," that are readily filled and placed under the press and retain all the compression given them by the press after they are removed therefrom till it becomes necessary to remove the tobacco therefrom.

The construction of my compressors I prefer to make as follows, although several minor changes may be made in them without materially affecting the result:

a is an iron casting, consisting of a bed plate or bottom and two ends with a partition in the middle, by which two separate boxes are formed, or there may be a single box only in one casting. It will be seen in the drawings that the bottom projects beyond the open side at *b*, where there is a ledge projecting upward along its whole length. Into this recess a casting, *c*, fits, which is composed of two planes joined at right angles, the one forming the side and the other the bottom of the recess lying upon the bottom of the first-named casting, as shown at *c'*. The box thus formed receives the lump or roll of tobacco to be pressed, and upon this a thin plate, *d*, is placed, and another lump may then be added and another thin plate, or one may be pressed alone, according to the capacity of the compressor. When the box is filled, a follower, *f*, is put on, which just fills the space in the top of the box and projects above it a sufficient distance for the purpose required. It is then put altogether under a press of any descrip-

tion of sufficient power to make the proper compression and brought down to its bearings. On each side of the follower *f* are spring-bolts *e* that shoot outward. These are driven back as the follower enters the box, and when it has descended the proper distance the bolts are brought opposite holes or notches *h* in the side of the box and spring outward into said holes, and this secures the follower down. The compressor is then removed from the press and another put in, the operation going constantly on. When the lumps first compressed are sufficiently set to remain in shape after the pressure is relieved, the catches are forced back, so as to release the follower, and when that is removed the two side pieces are turned outward, as shown at *c''*, Fig. 1, and the tobacco can then be easily removed and the compressor freed for another operation. By this means the tobacco is rapidly and perfectly compressed, and the more powerful the pressure the closer the joints are held together.

It is obvious that a separate compressor detached from the press, with a follower which can be clamped down till the tobacco is set, may in their construction be variously modified, the mode of clamping may be different, and the parts of the compressor variously made, although I deem the one described the best.

It is also obvious that other vegetable products can be compressed in like manner, and I intend to apply my device to that purpose; also the numbers of cells can be varied and their size and form without changing the main features of my invention. Therefore,

What I claim as my invention, and for which I desire Letters Patent, is—

The construction and employment of a press-box or compressor, substantially as herein described, in which the article to be compressed can be put and placed under a press, and when compressed can be retained in that position and removed from the press till set, while the press is liberated for further operations, all as above set forth.

RHODOLPHUS KINSLEY.
